FUSE CONSTRUCTION

William O. Schultz, South Milwaukee, Wis., assignor to Line Material Company, South Milwaukee, Wis., a corporation of Delaware

Application August 12, 1937, Serial No. 158,653

25 Claims. (Cl. 200—116)

This invention relates to a fuse construction and is particularly directed to a fuse construction associated with a transformer or other electrical device.

5 This invention is intended to provide a fuse construction which is particularly useful on a single bushing transformer which is now quite common for rural service, though it is applicable to other types of transformers and in its 10 broadest aspect the invention is not limited to a fuse construction mounted upon a transformer. The single bushing transformers are made up with only one primary bushing, the other side of the primary winding being solidly grounded 15 to the transformer case.

Objects of this invention are to provide a fuse construction in which the fuse structure is carried by or supported from a base which may constitute the casing of a transformer, in which the 20 support may be, and usually is, of conducting material, as, for example, the metallic case of a transformer, and in which the arrangement of parts is such that under all conditions the discharge of gases and any metallic vapors from 25 the fuse is directed away from the metal base which, as stated, may be the metallic casing of the transformer.

Further and more specific objects are to provide a fuse construction in which the fuse unit, 30 such, for instance, as a fuse tube, rocks in a substantially horizontal position and swings about a substantially vertical pivot from operative to inoperative position, and in which the fuse tube may be readily removed from its support in a very simple manner, as, for example, 35 by lifting it directly upwardly from the pivot support to thus permit the complete removal of the fuse unit during re-fusing, the repositioning being equally simple and as easily performed.

40 Further objects are to provide a construction which is particularly suited for protecting a transformer, in which the fuse may be mounted on the transformer in a very simple manner, and in which surge protection is afforded even when 45 the fuse blows by the combined construction of fuse and spark gap.

Further objects are to provide a construction which is so made that the lineman may readily reclose the fuse by a horizontal motion without 50 the danger of the fuse discharging gases towards the lineman during this operation, the construction affording an easily manipulable fuse device which discharges the gases and metallic vapors in a substantially horizontal direction so that

the maximum safety for the lineman during reclosing of the device is thus afforded.

Further objects are to provide a fuse construction which is suitable for use on a transformer provided with a primary bushing, in 5 which the fuse is so made and the parts so arranged that the fuse unit is supported from the bushing of the transformer, and in which there are no excessive strains placed on this bushing either when the fuse blows or when it 10 is rocked back into operative position.

Embodiments of the invention are shown in the accompanying drawings, in which:

Figure 1 is a fragmentary side elevation showing one form of the invention. 15

Figure 2 is a plan view, with parts in section and broken away.

Figure 3 is a detail view of a modified form of fuse tube.

Figure 4 is a view corresponding to Figure 1 20 showing a further form of the invention.

Figure 5 is a horizontal view, partly in section with parts broken away, of the construction shown in Figure 4.

Figure 6 is a sectional view on the line 6—6 25 of Figure 5.

Figure 7 is a fragmentary view of the latching portion of Figure 5 showing the tip of the fuse cap in section.

In Figure 1 the metal casing of the transformer is indicated by the reference character 1, the insulating primary bushing by the reference character 2 and a supporting insulator by the reference character 3. A conductor, not shown, passes through the primary bushing 2 30 in the usual manner and terminates in the terminal member 4. This terminal member may be provided with a lower cap portion 5' which 35 directly contacts with the upper end of the insulating bushing 2.

The terminal member 4 is in the form of a housing and is provided with an upstanding pivot pin 5. Immediately above the pivot pin 40 the housing is cut away, as indicated at 6, and it is to be noted from Figure 2 that two sides 45 of the housing are open.

The fuse unit comprises the insulating fuse tube 7 which is open at both ends. The pivot end of the fuse tube is provided with a fitting 8 rigidly mounted thereon and pivotally supported on the pin 5.

The other or free end of the fuse tube is provided with an outwardly projecting arm or support 9 to which is pivoted the metal contact lever or movable contact 10 of the fuse tube. This 55

lever 10 may have upper and lower walls joined by an outer bridge piece 11 carrying the threaded stud 12 which receives the fuse link clamping nut 13 which clamps the free end of the leader 14 of the fuse link, the fuse link being provided with a fusible section 15 of reduced diameter and with an end button 16 which normally closes one of the open ends of the fuse tube, as shown in Figure 2. Preferably a leaf spring or contact spring 17 is carried within the terminal 4 and bears against the button or head 16 of the fuse link.

The contact lever 10 also constitutes a releasing member. It is held in place by the fuse link as long as the fuse link is intact. It is provided with a vertical end wall which constitutes a latch 18. This latch may have its face bevelled, as shown in Figure 2, for a purpose that will hereinafter appear.

20 The lever 10 straddles the supporting arm 9 and is pivoted thereto by the pivot pin 19. It is held in the position shown in Figure 2 when the fuse link is intact. Under normal conditions, that is to say, when the fuse is in operative position, the latch 18 of the lever 10 is positioned behind the outwardly turned latching member 20 of the spring 21.

In rocking the fuse about the pivot pin 5 towards closed position, it is obvious that the spring 21 is deflected by the bevelled face of the latch 18 and also due to the fact that the major portion of the spring 21, that is to say, that portion thereof which is first engaged by the latching lever or contact lever 10 when the tube is swung into closed position, is itself slanting and thus acts in the manner of a cam and is radially deflected to allow the latch 18 to pass behind the catch portion 20 of the spring. This spring also is provided with a curved bearing arm or contact portion 22 which engages the flat outer face of the member 18 and urges the fuse tube towards rocking motion about the pivot pin 5. The springs 21 and 22, which, as stated, may be integral if desired and as shown in Figure 2, are securely mounted on the terminal member 23, such terminal member being supported from the insulator 3 and being in the form of a small hood housing the major part of the lever 10 and housing the spring or springs 21 and 22. Preferably a terminal receiving contact tongue 24 is secured in direct contact with the contact spring, as shown most clearly in Figure 2.

The terminal member 23 has an outwardly and downwardly turned spark finger 25 which is positioned above the pin or finger 26 carried by the casing 1 so that the two fingers 25 and 26 constitute a spark gap for surge protection, the live side of the line being connected to the terminal member 23 through the medium of the contact tongue 24, for example.

It is obvious that under normal conditions the fuse is retained in its operative position, as shown in Figures 1 and 2. However, when an overload occurs, the gases are expelled from the open end of the fuse tube adjacent the contact and latching lever 10. The pressure of the spring 22 urges the fuse tube towards rocking motion about the pivot pin 5 and the contact spring 17 also urges the tube in the same direction. It is clear that when the fuse link is ruptured, the lever 10 is released and rocks to releasing position free of the latching spring 21 and thus allows the fuse tube to rock about the pivot pin 5 from operative to inoperative position.

75 The device may be readily re-fused as it is

clear that the fitting 8 will rock into such a position that the fuse tube may be lifted directly upwardly, the fitting 8 or pivot support arm rigidly carried by the fuse tube being then at that point of the terminal member or housing 4 which is cut out, as is indicated at 6 in Figure 2. Obviously, therefore, the fuse may be removed by lifting it directly upwardly. It may be re-fused and may be replaced. Thereafter the lineman, through the medium of suitable instruments, for instance a switch stick, may push the fuse into closed position, the latch 18 freely riding into locking position behind the spring 21.

It is obvious that the device need not necessarily employ a fuse tube open at both ends, as shown in Figure 2, as obviously the usual terminal 27 may be carried by the fuse tube 28, see Figure 3, and the terminal cap 29 may be screwed onto the terminal to clamp the end button of the fuse link in place in accordance with the usual practice.

Referring to the form of the invention shown in Figures 4 to 7 the same general principle of construction is followed as that hereinbefore described. The transformer casing is indicated at 30, the primary bushing at 31 and the terminal for the primary winding at 32. This terminal preferably includes an upright portion as shown in Figures 4 and 5 to which is bolted a U-shaped spring contact member 33. This contact member is of double or looped, relatively springy construction and the two arms thereof are substantially parallel throughout the major part of their length and are bent into a U-shape, as viewed in Figure 5. Preferably a small retaining clamp 34 is carried by the arms 33 and is provided with overlapping lips to prevent relative shifting of the arms 33. The arms 33 diverge, as indicated at 33' in Figure 7, to provide a guiding section for guiding the tip 35 of the contact cap 36 of the fuse tube 37. The arms 33 are bent inwardly to provide a retaining shoulder 38 which normally retains the tip 35 or outer contact of the fuse tube in position. The arms 33 bear outwardly against the flat face of the contact cap 36 of the fuse tube and thus insure good contact when the fuse is in operative position.

It is preferable to provide a metal ring or plate 39 at the lower end of the bushing 31, see Figure 4. This forms a support to which the upwardly and outwardly extending metallic supporting arm 40 is secured by welding or in any other suitable manner, or, if desired, the arm 40 can be made integral with the member 39. The metal plate 39 and the arm 40 constitute a metallic support which is grounded on the metallic casing 30. The arm 40 carries the supporting insulator 41 which in turn carries the terminal 42, which is adapted to be connected in any suitable manner, as by means of the connector 43, with the live side of the incoming line. The terminal 42 includes a vertical pin 44 and a spark finger 45 extends outwardly from the terminal and projects downwardly towards the adjustable spark finger 46 carried by the supporting arm 40.

The fuse tube 37 is provided with an outwardly projecting arm 47 which is pivoted to the bifurcated contact lever 48. This lever is provided with a bridge piece 49 to which the leader 50 of the fuse link is clamped by means of the thumb nut 51, as shown most clearly in Figure 5, the fuse link including a reduced fusible section 52, the end button of the fuse link being clamped be- 75

tween the fitting 53 and the terminal cap 36 in the usual manner.

The lever 48 has its two arms joined by a sleeve 54 and also joined by a web 55 spaced from the sleeve 54, as shown in Figure 5. The lever 48 is pivotally and removably mounted upon the vertical pin 44.

A spring 56 is coiled about the sleeve 54 and has one end bearing against the upstanding portion 10 of the terminal 42 and the other end bearing against a pin 58 carried by the lever 48. A much lighter spring 57 is coiled about the pivot pin 57' and has one end bearing against an extension 47' of the arm 47. The relatively heavy spring 15 56 tends to rock the lever 48 in a counterclockwise direction, and the relatively lighter spring 57 tends to rock the tube 37 in a counterclockwise direction about the pivot pin 57', that is to say, the relatively lighter spring 57 tends to maintain 20 the tube 37 and the lever 48 in their relative positions, as shown in Figure 5.

When the fuse blows, the metallic gases and metallic vapors are expelled in a horizontal direction out of contact with either the metal supporting arm 40 or the metal casing 30 of the 25 transformer. Rupturing of the fuse link releases the lever 48 and allows the lever to rock in a counterclockwise direction under the influence of the relatively heavy spring 56 and this withdraws 30 the tip 35 from the contact arms 33. The action of the heavy spring is opposed to that of the lighter spring 57. However, as the tube moves towards inoperative position under the influence of the spring 56 due to the rotation of the lever 35 48 about its pivot 44, the tip 35 of the outer contact of the fuse tube clears the contact arms 33 and the spring rocks the tube outwardly clear of the stationary contact.

The lighter spring 57 now comes into play and 40 moves the tube 37 up against the arm of the lever 48 so that the lever 48 and the tube 37 occupy the same relative position as they are shown in Figure 5. The spring 56, however, rotates the tube 37 and lever 48 until the tube is approximately 45 at right angles to the position shown in Figure 5. The tube cannot loosely rock about the pivot pin 57' as the spring 57 maintains the same relative position of the tube 37 and lever 48.

Obviously in re-fusing it is merely necessary 50 to lift the fuse unit upwardly from the pin 44. Thereafter it may be readily re-fused and replaced after re-fusing upon the pin 44 and rocked back into service, preferably a manipulating eyelet member 59, see Figure 5, being provided.

55 It will be seen that a novel form of fuse construction has been provided by this invention in which the fuse swings in a horizontal direction and the discharging gases and metallic vapors are projected in a horizontal direction away from the 60 transformer casing or other metallic support upon which the fuse construction may be carried. Also it is a simple matter for a lineman to re-fuse the device after it is detached and to rock it into place by a horizontal swinging motion imparted 65 to the fuse unit by a switch stick or other suitable member so that even if the fuse blows immediately upon reclosing, the discharge of gases is away from the lineman and is not downwardly in a direction towards the lineman. Greater safety 70 is thus secured and extreme ease in the manipulation of the device is obtained.

Further the construction is very simple and employs a relatively small number of simple and relatively inexpensive parts.

75 It is to be noted that the form of horizontal

swinging tube construction shown in Figure 1 could be employed as a unitary structure, as shown in Figure 4, or the form of horizontal swinging tube construction shown in Figure 4 could be carried on insulators from the transformer housing or any other support without departing from the spirit of this invention.

Although this invention has been described in considerable detail, it is to be understood that such description is intended as illustrative rather than limiting, as the invention may be variously embodied and is to be interpreted as claimed.

I claim:

1. A fuse construction comprising a support, a fuse unit adapted to move laterally in a substantially horizontal plane spaced from said support, a pair of terminals normally electrically connected by said fuse unit, said fuse unit being movably supported from one terminal and having a free end movable away from the other terminal from operative to inoperative position, and latch means normally holding said fuse unit in operative position, said fuse unit including a fuse link normally restraining said latch means from releasing.

2. A fuse construction comprising a support, a fuse unit adapted to swing laterally in a substantially horizontal plane spaced from said support, a pair of terminals normally electrically connected by said fuse unit, said fuse unit being pivotally supported from one terminal and having a free end adapted to swing away from the other terminal from operative to inoperative position, and latch means normally holding said fuse unit in operative position, said fuse unit including a fuse link normally restraining said latch means from releasing.

3. A horizontal fuse construction comprising spaced terminal members, a fuse unit normally electrically connecting said terminal members, means movably supporting said fuse unit for horizontal motion away from one of said terminal members from operative to inoperative position, and means biasing said fuse unit for motion towards inoperative position, said fuse unit including a fuse link normally restraining said fuse unit against motion towards inoperative position.

4. A horizontal fuse construction comprising a pair of spaced contacts one of which is provided with a substantially vertical pivot pin, a fuse unit 50 normally electrically connecting said contacts and being pivoted upon said pin adjacent one end and having a free end normally engaging the other of said contacts, means biasing said fuse unit for swinging motion about said pin, and a fuse link 55 normally restraining said fuse unit against swinging motion.

5. A horizontal fuse construction comprising a pair of spaced contacts one of which is provided with a substantially vertical pivot pin, a fuse unit 60 normally electrically connecting said contacts and being pivoted upon said pin adjacent one end and having a free end normally engaging the other of said contacts, means biasing said fuse unit for swinging motion about said pin, latch means having a portion movable with respect to said fuse unit for normally preventing swinging motion of said fuse unit, and a fuse link normally holding said latch means against releasing motion.

6. A fuse construction comprising a pair of 70 stationary contacts, one of said contacts having a substantially vertically arranged pivot member, a fuse unit mounted in a substantially horizontal position and supported from said pivot member adjacent one end, cooperating releasable latching 75

means having parts carried jointly by the other end of said fuse unit and the other of said stationary contacts, means urging said fuse unit in a direction to move said last mentioned end away from said last mentioned stationary contact, and a fuse link forming a portion of said fuse unit and normally restraining said latching means against releasing motion.

7. A fuse construction comprising a pair of stationary contact members, a fuse unit pivotally mounted adjacent one end of said unit upon one of said stationary contact members, means biasing said fuse unit towards pivotal motion in a substantially horizontal direction, releasable means temporarily locking the other end of said fuse unit to the other of said stationary contact members, and a fuse link restraining said releasable means against releasing motion.

20 8. A fuse construction comprising a pair of stationary contacts, one of said stationary contacts having a substantially vertical pivot member, a fuse tube provided with a fitting adjacent one end pivotally mounted upon said pivot member and supporting said fuse tube for horizontal swing motion about said pivot member, the other of said stationary contacts having catch means, and a latching member carried by the other end of said fuse tube and detachably engaging said catch means, said fuse construction including
25 means biasing said fuse tube towards pivotal motion about said pivot member, and a fuse link carried by said fuse tube and normally restraining said latching member against releasing motion.

9. A fuse construction comprising a pair of spaced insulating members, a pair of stationary contacts carried by said insulating members, one of said stationary contacts having a substantially vertical pivot pin and having a housing with a cut away portion adjacent said pin, a fuse tube having an arm rigidly mounted thereon and projecting from adjacent one end and pivotally mounted upon said pivot pin, the other end of said fuse tube being free, said fuse tube being removable from said pivot pin when said arm is swung into a position adjacent the cut away portion of said housing, means biasing said fuse tube towards pivotal motion about said pivot pin, and a fuse link normally electrically connecting said stationary contacts and restraining the free end of said fuse tube from motion away from said last mentioned stationary contact.

10. A fuse construction comprising a pair of stationary contacts, each of said stationary contacts including a housing, one of said stationary contacts having a substantially vertical pivot member, a fuse tube supported adjacent one end from said pivot member and having such end normally located within the housing of the corresponding stationary contact, the other end of said fuse tube being free, catch means housed within the housing in the other of said stationary contacts, a releasable latch member projecting from the free end of said fuse tube and normally projecting into the housing of the last mentioned stationary contact and releasably engaging said latch, said fuse construction including means biasing said fuse tube for pivotal motion about said pivot member, and a fuse link normally restraining said latch against releasing motion.

11. In an apparatus of the class described, an electrical device having a metal casing, an insulating bushing carried by said casing and supporting a stationary contact having a substantially vertically arranged pivot member, a fuse tube mounted in a substantially horizontal position and laterally against the casing.

tion and having means cooperating with said substantially vertical pivot member to pivotally support said tube for horizontal swinging motion about said pivot member, means biasing said fuse tube towards swinging motion, a second insulating member provided with a second stationary contact, releasable latch means normally holding said fuse tube against swinging motion, and a fuse link carried by said fuse tube and restraining said latch means against releasing motion.

12. A fuse construction comprising a pair of spaced insulating members, a stationary contact carried by one of said insulating members and including catch means, a second stationary contact carried by the other of said insulating members and having a substantially vertically positioned pivot member, a fuse tube having a free end normally engaging said catch means, supporting means carried adjacent the other end of said fuse tube and pivotally supported from said pivot member, said supporting means pivotally supporting said fuse tube from said pivot member for swinging motion about said pivot member and releasably holding the free end of said fuse tube in engagement with said catch means, means biasing said fuse tube for swinging motion about said pivot member, and a fuse link controlling the action of said supporting means. 16
20
25

13. A unitary fuse construction comprising a conducting supporting member adapted to be attached to a suitable support, a pair of insulators projecting upwardly therefrom, said insulators having stationary contacts and one of said contacts having a pivot support, a fuse tube pivotally supported adjacent one end thereof from one of said stationary contacts and mounted in a horizontal position for swinging motion in a horizontal plane about the pivot support, said fuse tube having a free end, the other of said stationary contacts including catch means normally engaging the free end of said fuse tube, means biasing said fuse tube for horizontal swinging motion about the pivot support, and a fuse link restraining said fuse tube against swinging motion. 30 35 40

44
14. A fuse construction comprising a pair of spaced stationary contacts, one of said contacts having a substantially vertical pivot member, the other of said contacts having latch means, a fuse tube mounted in a horizontal position, jointed link mechanism adjacent one end of said fuse tube and pivotally supported from said pivot member for supporting said fuse tube for swinging motion in a horizontal plane about said pivot member, said jointed link mechanism normally holding the other end of said fuse tube in latching relation to said latch means, means biasing said fuse tube towards swinging motion, and a fuse link normally holding said jointed link mechanism against releasing motion.

55

15. A fuse construction comprising a pair of spaced stationary contacts, one of said contacts having a substantially vertical pivot member, the other of said contacts having latch means, a fuse tube mounted in a horizontal position, jointed link mechanism adjacent one end of said fuse tube and pivotally supported from said pivot member for supporting said fuse tube for swinging motion in a horizontal plane about said pivot member, said jointed link mechanism normally holding the other end of said fuse tube in latching relation to said latch means, means biasing said fuse tube towards swinging motion, and a fuse link normally holding said jointed link mechanism against releasing motion, said jointed link mechanism being freely removable from said 75

5 pivot member, whereby said fuse tube may be removed for re-fusing.

6 16. In an apparatus of the class described, an electrical device having a metal casing, a metal support supported from and electrically connected to said casing, an insulating bushing extending upwardly from said metal support and having an upper stationary contact, a spaced insulating member carried by said metal support and having a second stationary contact, a fuse tube mounted in a horizontal position and having a free end adjacent said first mentioned contact, said first mentioned contact including latch means normally holding the free end of said fuse tube, jointed link mechanism adjacent the other end of said fuse tube, pivot means supporting said jointed link mechanism and said fuse tube from said second mentioned contact, said jointed link mechanism normally holding the free end of said fuse tube in latching relation to said latch means, means biasing said fuse tube towards horizontal swinging motion, and a fuse link carried by said fuse tube and holding said jointed link mechanism against releasing motion.

25 17. In an apparatus of the class described, an electrical device having a metal casing, a metal support supported from and electrically connected to said casing, an insulating bushing extending upwardly from said metal support and having an upper stationary contact, a spaced insulating member carried by said metal support and having a second stationary contact, a fuse tube mounted in a horizontal position and having a free end adjacent said first mentioned contact, said first mentioned contact including latch means normally holding the free end of said fuse tube, jointed link mechanism adjacent the other end of said fuse tube, pivot means supporting said jointed link mechanism and said fuse tube from said second mentioned contact, said jointed link mechanism normally holding the free end of said fuse tube in latching relation to said latch means, means biasing said fuse tube towards horizontal swinging motion, a fuse link carried by said fuse tube and holding said jointed link mechanism against releasing motion, and spark gap means between said second mentioned contact and said metal support.

50 18. In a fuse construction, a pair of spaced insulating members, a first and a second contact member carried by said insulating members, said first contact member having latch means including a pair of spring jaws having divergent outer ends and having a constricted neck portion formed between said jaws, a fuse tube having a free end provided with a metal cap having a projection normally held by the constricted portion of said latch means, the second of said contact members having a substantially vertical pivot pin, jointed link mechanism supporting said fuse tube from said pivot pin for swinging motion in a horizontal plane, said jointed link mechanism normally holding said cap in latching engagement with said latch means, means biasing said fuse

55 tube for swinging motion about said pivot pin, and a fuse link carried by said fuse tube and normally holding said jointed link mechanism against releasing motion.

60 19. In a fuse construction, a pair of spaced insulating members, a first and a second contact member carried by said insulating members, said first contact member having latch means including a pair of spring jaws having divergent outer ends and having a constricted neck portion formed between said jaws, a fuse tube having a

free end provided with a metal cap having a projection normally held by the constricted portion of said latch means, the second of said contact members having a substantially vertical pivot pin, jointed link mechanism supporting said fuse tube from said pivot pin for swinging motion in a horizontal plane, said jointed link mechanism normally holding said cap in latching engagement with said latch means, means biasing said fuse tube for swinging motion about said pivot pin, a fuse link carried by said fuse tube and normally holding said jointed link mechanism against releasing motion, said jointed link mechanism being freely removable directly upwardly from said pivot pin, whereby said fuse tube may be freely removed for re-fusing.

65 20. In an apparatus of the class described, an electrical device having a metal casing, an insulating bushing projecting upwardly from said casing and having an upper contact, an insulator supported from said casing and having an upper contact, an expulsion fuse tube mounted in a horizontal position above said casing, pivot means carried by one of said contacts for pivotally supporting said fuse tube for swinging motion in a horizontal plane whereby the discharge of gases from said expulsion fuse tube will take place in a horizontal plane above said casing, means biasing said fuse tube toward swinging motion, and a fuse link carried by said fuse tube and normally restraining said fuse tube from swinging motion.

70 21. In an apparatus of the class described, a metal support, an insulating bushing extending upwardly from said metal support and having an upper stationary contact, a spaced insulating member carried by said metal support and having a secondary stationary contact, a fuse tube mounted in a horizontal position and pivotally supported adjacent one end from one of said stationary contacts and having a free end normally connected to the other of said stationary contacts, means biasing said fuse tube towards horizontal swinging motion, and a fuse link restraining said fuse tube from swinging motion.

75 22. A fuse construction comprising a support having spaced terminals, one of said terminals having pivot means and the other of said terminals having stationary contact means, a fuse tube movable from operative to inoperative position and having one end normally held by said stationary contact means, a lever pivoted on said pivot means and pivoted to said fuse tube and normally positioned adjacent said fuse tube, said lever releasing said fuse tube from said stationary contact means when said lever moves away from said fuse tube, said fuse tube being biased towards inoperative position, a fuse link in said fuse tube normally restraining said lever against releasing motion and electrically connecting said lever and said stationary contact means, and a spring biasing said lever towards said fuse tube after said fuse tube has been released from said stationary contact means.

80 23. A fuse construction comprising a support, a pair of spaced terminals carried by said support, one of said terminals having vertically arranged pivot means and the other of said terminals having stationary contact means, a fuse tube having one end normally held by said stationary contact means and movable from operative to inoperative position, a lever pivoted on said pivot means and pivoted to said fuse tube, said fuse tube being biased towards swinging motion in a horizontal plane about said pivot means,

- said lever normally holding said fuse tube in engagement with said stationary contact means and being normally positioned adjacent said fuse tube, a fuse link within said fuse tube electrically connecting said lever and said stationary contact means and normally restraining said lever against releasing motion, and a spring biasing said lever towards said fuse tube after said fuse tube has been released from said stationary contact means.
24. A fuse construction comprising a terminal having pivot means, a fuse tube pivoted on said pivot means and having a free end adapted to swing with reference to said pivot means, a latch carried by said free end, a second terminal having a catch normally engaged by said latch and restraining said fuse tube against swinging motion, a fuse link normally restraining said latch against releasing motion and electrically con-
- 5
10
15

necting said terminals, and a spring carried by said second terminal and urging said fuse tube against swinging motion.

25. A fuse construction comprising a first terminal having pivot means, a fuse tube pivotally supported from said pivot means and having a free end, said fuse tube being open at each end, a latch carried by the free end of said fuse tube, a second terminal provided with a catch normally engaged by said latch, a headed fuse link 10 extending through said fuse tube and electrically connecting said terminals, said fuse link having the head thereof located at the end of the fuse tube adjacent the pivot means and having its other end restraining said latch, and a spring 15 bearing against the headed end of said fuse link and urging said fuse tube towards swinging motion about said pivot means.

WILLIAM O. SCHULTZ.
